Ray Miller Peterma

UNITED STATES PATENT OFFICE.

RAY MILLER PETERSIME, OF GETTYSBURG, OHIO.

REGULATOR.

Application filed January 7, 1926. Serial No. 79,850.

This invention relates to regulators, and more particularly to a thermostatic controlled regulator for use in incubators and the like, for making and breaking an electric circuit to a heater.

The primary object of my invention is the provision of a regulator which will efficiently make and break an electric circuit in a sudden or quick manner, so as not to fuse 10 the points or contacts, or to form an arc therebetween which is very detrimental to contacts.

A further object of the invention is to provide a regulator as above outlined having a movably mounted contact arm provided with a contact on one end thereof adapted to engage a permanent contact, the movement of said arm being controlled by a member operated by a thermostat and 15 having means thereon which when moved past the dead center at its point of engagement with the movable arm will suddenly move said arm to either make or break a circuit to a heater wired to the contacts.

20 A still further object of the invention is the provision of a safety member operated by the thermostat and connected to the contact arm for assuring movement of the movable contact arm in order to engage or disengage the contacts as the temperature at the thermostat rises above or falls below predetermined degrees.

It is also an object of the invention to provide a device of the above indicated character, which is simple and substantial in construction, which can be manufactured economically, and which will be thoroughly efficient and practical in use.

With the foregoing and other objects in view, which will be apparent as the description proceeds, the invention resides in the construction and arrangement of parts, as hereinafter described and claimed, it being understood that changes can be made 40 within the scope of what is claimed, without departing from the spirit of the invention.

The invention is illustrated in the accompanying drawings, wherein:

50 Figure 1 is a side elevation of my improved regulator,

Figure 2 is a horizontal section taken on line 2—2 of Figure 1,

Figure 3 is a fragmentary vertical section 55 taken on line 3—3 of Figure 2, and

Figure 4 is a cross vertical section taken on line 4—4 of Figure 3.

Referring to the drawings by numerals, a stationary arm or bracket 10 is provided which consists of a channel bar bent in the 60 form of a right angle one member of which is provided with an attaching flange 11 through which screws or the like are passed to rigidly secure the arm or bracket in place. Pivotedly connected to this stationary arm 65 or bracket 10 is a movable arm 13, the inner end of which is provided with a pair of ears 14 extending between the side flanges of the channel member forming the arm or bracket to receive the rivet 12. The movable arm 70 13 is also of channel formation to reinforce the same against bending or flexing while in operation.

Positioned between the outer portion of the bracket 10 and the movable arm 13 is a 75 series of thermostatic wafers 15, secured to the movable arm 13, as at 16, and an adjusting screw 17 carried by the arm of the bracket is adapted to engage the outer end of the series of wafers 15 so as to cause the 80 movable arm 13 to be swung on its pivot when said thermostatic wafers are expanded due to excessive temperature. A lock nut 18 is provided for locking the adjusting screw in a desired position against accidental 85 movement.

Attached at one end to the movable arm 13 is a coil spring 19, the attachment being made by looping the end of the spring through a pair of small openings in the arm 90 13. The other end of the coil spring is attached to the outer end of a threaded rod 20 which extends through an opening therefor in the stationary arm or bracket and is provided with a nut 21 engaging the arm of the bracket whereby the tension of the coil spring 19 may be varied, said coil spring being for the purpose of yieldably drawing the movable arm 13 towards the bracket.

The stationary arm or bracket 10 has a 100 pair of upstanding spaced ears near its outer end to receive therebetween a contact arm 23, having a pair of down-turned flanges 24, at each side thereof adjacent one end through which a rivet, or the like, 25 passes 105 from the upstanding ears 22 on the stationary arm 10 for pivotally supporting said contact arm on the bracket. On the inner end of the arm 23 is a contact member 24 insulated from the arm by means of insula- 110

tion 25', and a like contact member 26 is carried by the bracket and insulated therefrom as at 27. The contact members 24' and 26 are adapted to engage and disengage each other when the arm 23 is swung upon its pivotal connection 25, and each of these contact devices is provided with a binding nut for connecting the electric wires thereto.

On the outer end of the contact arm 23, 10 between the down-turned flanges 24 thereof is a roller 29, mounted on a pin 30 extending between said flanges, and cooperating with this roller is a leaf spring 31 attached to the outer end of the movable arm by screw 33 15 and extending downwardly therefrom is provided with a small offset or inturned projection 32 at the point where said leaf spring engages the roller. By extending the inner end of the leaf spring between the side 20 flanges of the arm 13 and securing the same to the intermediate wall, it is held against turning or twisting movement. In order to adjust the tension of the leaf spring against the roller 29, the free end of the arm 13 is 25 turned downwardly, as at 34, and has an adjusting screw 35 threaded therethrough adapted to engage the leaf spring 31 to either force the same away from the roller 29 or permit the spring to bear tightly there- 30 against. A lock nut 36 is carried by the screw 35 for locking the same against accidental movement. It can be seen that when the arm 13 is forced upwardly the projection 32 on the leaf spring will bear against the 35 roller 29 holding the contacts snugly in engagement with each other until said projection has passed dead center at its point of engagement with the roller 29, at which time the spring tension of the leaf spring 40 will force the projection inwardly thus causing the outer end of the contact arm having the roller thereon to be swung downwardly, raising or disengaging the contacts 24' and 26.

45 Carried by the movable arm 13 is a downwardly extending or depending bar 38, having notches 39 in its opposite edges at the point where it extends through an opening 40 in the contact arm 23, so as to loosely connect the contact arm 23 to the movable arm 13. The notches in the edges of the bar 38 are of sufficient length so that the bar only engages the contact arm 23 should the small projection 32 arranged on the leaf 50 spring 31 fail to properly swing the contact arm 23 when the movable arm 13 is moved by the thermostat, thus providing a safety device which will assure the engaging and disengaging of the contacts when the temperature at the thermostat rises or falls.

60 In operation, wires are connected to the contact members 24' and 26 which when in engagement with each other will permit current to flow to an electric heater, or the like.

65 When the temperature at the thermostatic

wafers 15 reaches a predetermined point, regulated by means of the screw 17, the arm 13 will be swung upwardly against the tension of the spring 19. As the arm 13 is moved upwardly, the small projection 32 on the leaf spring 31 engages under the roller 29 and forces the leaf spring slightly outwardly as the arm 13 continues to move upwardly. When the projection 32 has passed dead center of the roller 29, the spring tension of the leaf spring 31 will move said projection suddenly inwardly giving a quick downward movement of the outer end of the contact arm 23 having the roller thereon, thus swinging the inner end of said contact arm upwardly and disengaging the contacts 24' and 25. As the current is broken rather suddenly an arc will not be formed between the contacts, which would tend to fuse same and destroy the faces thereof.

80 As soon as the contacts are disengaged the current to the heater is cut off, and as the temperature decreases the arm 13 returns slowly to its initial or normal position, due to the spring 19. As the arm 13 returns to its normal position the projection 32 on the leaf spring 31 will engage the roller 29 on the contact arm 23 and cause the arm 23 to have a slight, quick, or sudden movement when the projection passes the roller 29, 95 which will return the contacts to engagement with each other.

90 From the foregoing it can be seen that I have provided a regulator which will efficiently make and break an electric circuit in a sudden or quick manner, a very desirable feature in regulators of this general type 100 which are used for various purposes.

Having thus described my invention, what I claim as new is:

105 1. A regulator comprising a stationary arm, a movable arm pivoted at one end thereto, a thermostat interposed between said arms for imparting movement to the movable arm, a contact-arm pivoted to the stationary arm and adapted to engage a contact on said arm, means responsive to the movement of the movable arm for swinging the contact-arm in engaging and disengaging the contacts, and auxiliary means responsive to the movement of the movable arm for operating the contact-arm on excessive movement of the movable arm in either direction.

110 2. A regulator comprising a stationary arm, a movable arm, a thermostat arranged between said arms for moving said movable arm, a contact arm pivotally carried by said stationary arm and having a contact on one end thereof, a stationary contact adapted to be engaged and disengaged by said contact on said contact arm, means carried by said movable arm and engaging said contact arm for swinging said contact arm upon movement of said movable arm, and a positive 115 120 125 130

means carried by said movable arm and connected to said contact arm for assuring the engaging or disengaging of said contacts should said means carried by said movable arm which engages said contact arm fail to operate.

3. A regulator comprising a stationary arm, a movable arm, a thermostat arranged between said stationary arm and movable arm for moving said movable arm away from said stationary arm, spring means for returning said movable arm towards said stationary arm when said thermostat contracts, a contact arm pivotally carried by said stationary arm and having a contact arranged upon the same, a stationary contact adapted to be engaged and disengaged by said contact on said contact arm, a leaf spring carried by said movable arm and yieldably engaging said contact arm, and an off-set portion formed on said leaf spring for engaging said contact arm in order to swing the same on its pivot upon movement of said movable arm.

25 4. A regulator comprising a stationary arm, a movable arm, a thermostat arranged between said stationary arm and movable arm for moving said movable arm away from said stationary arm, spring means for returning said movable arm towards said stationary arm when said thermostat contracts, a contact arm pivotally carried by said stationary arm and having a contact arranged upon the same, a stationary contact adapted to be engaged and disengaged by said contact on said contact arm, a leaf spring carried by said movable arm and yieldably engaging said contact arm, an in-turned projection carried by said leaf spring and adapted to engage one end of said contact arm for swinging said contact arm on its pivot when said projection moves past the point of dead center at its point of engagement with said contact arm.

45 5. A regulator comprising a stationary arm, a movable arm, a thermostat arranged between said stationary arm and movable arm for moving said movable arm away from said stationary arm, spring means for returning said movable arm towards said stationary arm when said thermostat contracts, a contact arm pivotally carried by said stationary arm and having a contact arranged upon the same, a stationary contact adapted to be engaged and disengaged by said contact on said contact arm, a leaf spring carried by said movable arm and yieldably engaging said contact arm, an in-turned projection carried by said leaf spring and adapted to engage one end of said contact arm for swinging said contact arm on its pivot when said projection moves past the point of dead center at its point of engagement with said contact arm, and means for adjusting the tension of said leaf spring.

6. A regulator comprising a stationary arm, a movable arm, a thermostat arranged for moving said movable arm, a contact arm pivotally mounted and having a contact on one end thereof, a stationary contact adapted to be engaged and disengaged by said contact on said contact arm upon movement of said contact arm, a yieldable member carried by said movable arm, a roller mounted upon one end of said contact arm and engaged by said yieldable member carried by said movable arm, and a projection carried by said yieldable member and adapted to swing said contact arm on its pivot when said projection is moved past the point of dead center of its engagement with said roller.

7. A regulator comprising a stationary arm, a movable arm, a thermostat arranged for moving said movable arm, a contact arm pivotally mounted and having a contact on one end thereof, a stationary contact adapted to be engaged and disengaged by said contact on said contact arm upon movement of said contact arm, a yieldable member carried by said movable arm, a roller mounted upon one end of said contact arm and engaged by said yieldable member carried by said movable arm, a projection carried by said yieldable member and adapted to swing said contact arm on its pivot when said projection is moved past the point of dead center of its engagement with said roller, and means for adjusting the tension of said yieldable member.

8. A regulator comprising a movable arm, a thermostat arranged for moving said movable arm, a pivotally mounted contact arm having a contact carried by one end thereof, a stationary contact adapted to be engaged by said contact on said contact arm, means carried by said movable arm and engaging said contact arm for swinging said contact arm upon movement of said movable arm, and means carried by said movable arm and connected to said contact arm for assuring movement of said contact arm upon movement of said movable arm should said means engaging said contact arm and carried by said movable arm fail to function.

9. A regulator comprising a movable arm, a thermostat arranged for moving said arm, a pivoted contact arm, a contact carried by one end of said contact arm, a stationary contact adapted to be engaged and disengaged by said first mentioned contact, a roller provided on said contact arm, a depending member carried by said movable arm, a projection arranged upon said depending member and adapted to move said contact arm when said projection is moved to a point past dead center at its engagement with said roller, and means for adjusting the tension of said depending member against said roller.

10. A regulator comprising a movable arm, a thermostat adapted to move said movable arm, a circuit making and breaking structure adapted to be operated by the movement of said movable arm, and a bar carried by said movable arm and being loosely connected to said circuit making and breaking structure so as to make or break the circuit upon extreme movement of said movable arm in either direction should said first mentioned circuit making and breaking structure fail to operate.
11. A regulator comprising a stationary arm arranged in angle formation, a movable arm pivotally connected to one angled portion of said stationary arm, a thermostat positioned between the other angled portion of said stationary arm and the movable arm for moving said movable arm, an adjusting screw for adjusting the degree of temperature said movable arm will be moved at, spring means for returning said movable arm when the thermostat contracts, a contact bar pivotally mounted upon said stationary arm, a contact upon one end of said contact arm, a stationary contact adapted to be engaged and disengaged by said contact on said contact arm, a roller provided upon one end of said contact arm, a leaf spring carried by said movable arm and extending downwardly and yieldably engaging said roller, a depending portion formed on said movable arm, an adjusting screw threaded through said depending portion and engaging said leaf spring for varying the tension thereof against said roller, a projection formed on said leaf spring and adapted to swing said contact arm on its pivot when said projection is moved to a point slightly to one side of dead center of said roller, and a depending bar formed on said movable arm and having notches formed in the sides thereof, said contact arm having an opening formed therein for receiving the notched portion of the depending bar, said notches being of sufficient size so as to only move said contact arm upon movement of the movable arm should the projection on the leaf spring fail to move the contact arm.
12. A regulator comprising a stationary arm arranged in angle formation, a movable arm pivotally connected to one angled portion of said stationary arm, a thermostat positioned between the other angled portion of said stationary arm and the movable arm for moving said movable arm, an adjusting screw for adjusting the degree of temperature said movable arm will be moved at, spring means for returning said movable arm when the thermostat contracts, a contact bar pivotally mounted upon said stationary arm, a contact upon one end of said contact arm, a stationary contact adapted to be engaged and disengaged by said contact on said contact arm, a roller provided upon one end of said contact arm, a leaf spring carried by said movable arm and extending downwardly and yieldably engaging said roller, a depending portion formed on said movable arm, an adjusting screw threaded through said depending portion and engaging said leaf spring for varying the tension thereof against said roller, a projection formed on said leaf spring and adapted to swing said contact arm on its pivot when said projection is moved to a point slightly to one side of dead center of said roller, and a depending bar formed on said movable arm and having notches formed in the sides thereof, said contact arm having an opening formed therein for receiving the notched portion of the depending bar, said notches being of sufficient size so as to only move said contact arm upon movement of the movable arm should the projection on the leaf spring fail to move the contact arm.

In testimony whereof, I have affixed my signature.

RAY MILLER PETERSIME.
